BOOK-BINDING MACHINE

John L. C. Mercer and Albert John Heath, London, England, assignors to James Burn & Co. Limited, London, England

Application November 29, 1948, Serial No. 62,504

Claims priority, application Great Britain
December 5, 1947

7 Claims. (Cl. 100—207)

1

This invention relates to bookbinding. When the sections of a book have been sewn and are stacked ready for binding, the thickness of the package is greater than that which is generally desirable in the bound book and is, moreover, greater at the spine edge than at the fore edge. In order to remove the "swell" at the spine edge and to reduce the overall thickness of the package, the package is usually compressed or "nipped" before it is bound. The nipping is usually effected in a press having a continuously vertically reciprocated head beneath which the packages are fed by hand.

In order to be effective, the nipping must expel the air from between the sheets. Care has to be taken to see that no air is trapped between the sheets during the nipping as such trapped air can lead to creasing or even bursting of the sheets. The operator ensures this by presenting the package to the press with the spine edges foremost so that about half the package is nipped and then, on the next stroke of the press, turning the package round so that the other half is nipped. If necessary, he finally puts the whole package into the press for a final overall nipping.

As the package is initially thicker at the spine edge than at the fore edge, there is a tendency, when the nipping pressure is applied, for the sheets to slide laterally on each other. This tendency has to be counteracted by the operator who does so by gripping the fore edge of the package strongly between his fingers. This is a difficult and tiring operation, particularly when working with highly glazed paper. The work is also dangerous as any carelessness may well result in the operator's fingers being crushed.

It is usual for two operators to work from opposite sides of one and the same press and a reasonable output from the press is about eight packages per minute.

A press with a semi-automatic feed is sometimes used. In this machine, a short belt conveyor is arranged with its upper run just above the bed of the press. The conveyor is fed by hand and is driven intermittently in synchronism with the reciprocation of the press so as to convey the packages under the head of the press and to remove them to a discharge point after they have been nipped. The nipping is effected at a single stroke of the press and, in order that this may be done, the operator has to "break" each package before it is fed to the press. This "breaking" consists in sharply bending the package about a line extending across the book from

spine to fore edge and is an operation which requires a considerable effort from the operator.

The machine in accordance with the invention is designed to reduce to a minimum the labour involved in nipping packages and to eliminate the necessity for skilled labour altogether.

It comprises an intermittently driven conveyor on which the packages are conveyed between horizontally adjustable, vertical guides to and through two successive nipping stations at each of which a pair of jaws is arranged so as to nip the books on the conveyor laterally between them.

The use of the machine involves a new method of nipping as the packages to be nipped are conveyed on edge step-by-step to the two nipping stations.

The packages are preferably nipped in the region of the spine at the first station and in the region of the fore-edge at the second station. In order to simulate the manual operation, the books are preferably subjected to a lateral pressure lighter than the nipping pressure in the region of the fore edge immediately before and during application of the nipping pressure at the spine edge at the first station and vice-versa at the second stage.

It is essential that the packages be fed through the machine in accurately controlled steps. If the steps through which the packages are advanced through the machine are as little as one hundredth of an inch too long, the cumulative error when say 1000 packages (much less than an hour's work) have been passed through would be 10 inches and the packages would, therefore not arrive accurately at the nipping stations.

The machine in accordance with the invention has means for rectifying any error in the length of a step of the conveyor. These means are of a simple nature and, in the preferred form of the machine, consist of a toothed segment or the equivalent which is brought into engagement with a toothed wheel forming part of the driving mechanism of the conveyor. The segment is brought into engagement after the wheel has been disconnected from the drive so that the wheel is accurately positioned.

An example of a machine in accordance with the invention will now be described with reference to the accompanying drawings in which:

Fig. 1 is a front elevation of the machine with certain parts shown broken away for the sake of clearness.

Fig. 2 is a plan of the machine.

55

Figs. 3 and 4 are sections to a larger scale taken respectively on the lines III-III and IV-IV in Fig. 1.

Fig. 5 is a section to a larger scale taken on the line V-V in Fig. 2.

Figs. 6 and 7 are sections taken respectively on the lines VI-VI and VII-VII in Fig. 5.

Fig. 8 is a section to a larger scale taken on the line VIII-VIII in Fig. 1.

Figs. 9 and 10 are respectively an elevation and a plan of a detail.

Fig. 11 is a section taken on line XI-XI in Fig. 10.

Fig. 12 is an enlarged elevation of part of Fig. 1.

The nipping machine shown in the drawings comprises a conveyor 10 which is intermittently actuated so as to convey the packages to be nipped to and through two nipping stations 12 and 14. The conveyor comprises a chain 16 passing round a pair of sprockets 18, 19 at each end of the machine. To the links of the chain are attached plates 20 which provide the carrying surface for the packages. At intervals, the conveyor is provided with brackets 22 which carry pushers as will be particularly described later on. The conveyor 10 is supported between the sprocket 18, 19, by a plate 24.

The sprocket 18 is the driving sprocket, the sprocket 19 is an idler. The sprocket 18 is connected by a unidirectional clutch or free-wheel device 26 to a connecting rod 27 which is adjustably attached by a pin-and-slot connection 28 to a lever 30 mounted to rock on a fixed pivot 32. The lever 30 has a counterweight 33 and a spring 34 which tend to keep a roller 35 carried by it pressed against a cam 36 on a shaft 38. Rotation of the cam 36 causes the lever 30 to be oscillated and the sprocket 18 to be intermittently driven through the one-way clutch 26. The latter is not shown in detail. It can be of any desired kind but is preferably of the well-known wedging ball type.

The packages to be conveyed through the machine are placed by hand on their spine edge on the conveyor at the loading station 40 as shown in chain lines in Fig. 3. The loading station is bounded laterally by a pair of guide plates 42, 44. The rear guide plate 42 is adjustable in accordance with the thickness of the package to be nipped. For this purpose it is carried by a pair of racks 46 supported in U-brackets 48 and meshing with pinions 50. The two pinions are fixed to a shaft 52 mounted in the brackets 48 and provided with a handwheel 54 (Fig. 2). Rotation of the hand wheel causes the wall 42 to be moved towards and away from the wall 44. A scale 56 is provided to enable the separation of the walls to be adjusted accurately. One leg of each bracket 48 is split and is provided with a clamping screw 57 by means of which the wall 42 can be locked in any adjusted position.

The wall 44 is pivotally mounted at 58 so that it can be swung away to widen the mouth of the loading station. It is connected by a link 60 to a lever 62 pivotally mounted at 64 and bearing against a cam 66 carried by the connecting rod 27. The wall 44 also has a rod 68 attached to it which can slide in a hole 70 in a bracket 72. The rod has a spring 75 on it which lies between the bracket 72 and a collar 76 on the rod and serves to keep the wall 44 swung towards the wall 42.

When the connecting rod 27 is making its idle stroke the cam 66 is brought into contact with

the lever 62 so that the wall 44 is swung outwards against the action of the spring 68. A package can then be dropped on to the conveyor so as to be ready to be conveyed through the machine when the conveyor is next actuated. During the early part of the movement of the conveyor, the lever 62 is carried away from the cam 66 and the package is gripped lightly by the walls 42, 44.

In case the conveyor should move a package forward while the front wall 44 at the loading station is swung outwards a guide surface 78 is provided to ensure that the package is not held back.

The conveyor moves the packages step-by-step towards the first nipping station 12. There, a pair of jaws 80, 82 is provided. The two jaws are alike in that they each comprise a backing plate 84 which is stepped at 86 and carries a yieldingly mounted plate 88. The plate 88 is mounted on pins 90 (Fig. 6) and is pressed away from the plate 84 by springs 92. When there is no package between the jaws, the plates 88 project slightly inwards from the plates 84 as indicated at 88' in Fig. 6. Similar parts on the respective opposite jaws are given the same numbers but followed by the letter b.

The front jaw 82 is fixed; the rear jaw 80 is mounted for reciprocation towards and away from the front jaw. For that purpose, the jaw 80 is connected by a link 93 to a connecting rod 94 (Fig. 4) driven by an eccentric 96 and pivotally connected by a link 98 to the frame 100, the links 93 and 98 thus forming a toggle.

When a package P is within the jaws at the nipping station 12 and the jaw 80 is moved towards the jaw 82, it is first gripped relatively lightly by the plates 88. This grip is equivalent to that which the operator applies by hand to the fore edge of the package as described earlier to hold the sheets against slipping during the nipping operation. The nipping is effected at the station 12 by the subsequent movement of the jaw 80 which causes the package P to be strongly gripped by the plates 84 in the region of the spine as shown in Fig. 6.

The jaw 80 is then moved away from the jaw 82 and when the package is thus released, it is conveyed by the conveyor to the second nipping station 14. At this station, there is a second pair of jaws 102, 104 which are of composite construction like the jaws 80, 82, having each a backing plate 105 and a yieldingly mounted plate 109. The jaws are stepped at 107 oppositely to the jaws at the first station. The plates 109 are mounted on pins 101 and are pressed inwards by springs 103.

The rear jaw 102 is mounted for reciprocation in exactly the same manner as the jaw 80. Similar reference numerals have been used in the drawings to indicate the parts of its driving mechanism.

It will be seen from Fig. 7 that when the jaw 102 is brought towards the jaw 104, the package P is first gripped lightly near the spine by the spring pressed plates 109 which project inwards from the plates 105 as indicated at 109' and the remainder of the package is then nipped strongly by the plates 105.

This completes the nipping. When the jaw 102 is moved back again, the conveyor conveys the completely nipped package out of the second nipping station 14 and to a discharging station 106 (see particularly Fig. 8).

At the discharging station, the nipped pack-

ages are supported between two guide rails 107, 108. The rear rail 107 is carried by a pair of arms 109 (only one is shown) depending from a shaft 110 carried by the frame of the machine. The front rail 108 is carried by a pair of short links 111 pivotally mounted on arms 112 depending from the shaft 110. An ejector 113 is also provided which is pivotally carried by a link 114 fixed to the shaft 110. The ejector is also pivotally connected by a link 115 to a shaft 116 which is fixed to the rear jaw 102 at the second nipping station.

It will be seen that the ejector is oscillated by and in synchronism with the rear jaw 102. When it is rocked forward, its lower end 117 is pressed against the package P at the discharge station below the level of the rear guide rail 107. The package is thus tilted as shown at P' in Fig. 8 and slides down a chute 118 the front guide rail 108 giving away as indicated at 108' in Fig. 8. On the return movement of the jaw, the ejector resumes its original position with the assistance of a spring 119. The front rail 108 falls back into its original position under its own weight, a stop (not shown) being provided to arrest the return motion in the position shown at 108 in Fig. 8.

Between the two nipping stations, a pair of guide walls 122, 124 is provided. The front wall 124 is fixed. The rear wall 122 is adjustable towards and away from the front wall in accordance with the thickness of the package being nipped by means similar to those provided for adjustment of the rear wall at the loading station 40. Similar reference numerals have been used in the drawings to indicate the parts of the adjusting means.

It is very important that the packages should be advanced by the conveyor in steps of exactly the right magnitude. This involves ensuring that the packages cannot slip on the conveyor and also ensuring that the conveyor itself makes steps of exactly the right magnitude. The pushers 22 preclude slip on the conveyor.

To ensure that the conveyor makes steps of the correct magnitude a positioning device 126 is provided (Figs. 1, 12 and 3). This device consists of a length of chain 128 exactly similar to the conveyor chain 16 and, therefore, fitting the teeth of the sprocket 18. The chain 128 is carried by a sector 130 pivotally mounted on a pin 132 carried by an arm 134. The arm 134 is free to turn on a fixed pin 136 as is an arm 138. The sector 130 is connected by a link 140 and an adjusting screw 142 to a lug 144 on the arm 138. The arm 138 has connected to it a link 146 carrying a roller 148 at its far end which bears against a cam 150 on the shaft 38 (Fig. 1). The link 146 is supported by a part 152 of the frame of the machine and the roller 148 is kept in contact with the cam 150 by a spring 154.

When the sprocket 18 is being driven, the roller 148 bears against the high part of the cam 150 and the chain 128 is held out of engagement with the sprocket as shown in chain dotted lines in Fig. 12. When, however, at the end of a driving stroke (position shown in Fig. 1), the movement of the connecting rod 27 is reversed and the sprocket is disconnected from the drive, the cam 150 lies in a position in which the roller 148 bears on its low part and the chain 128 is brought into engagement with the sprocket as shown in Figs. 1 and 12. The position of the chain is positively determined and therefore, the sprocket positions itself accordingly. The length of the stroke of

the conveyor is thus adjusted and it is thus ensured that any slight inaccuracy in the setting of the conveyor driving mechanism will not result in a cumulative error which would in time cause the packages to come to rest otherwise than within the jaws at the nipping stations.

A toothed sector could, of course, be used instead of the chain 128.

As has been described, the separation of the guide walls at the loading station and between the two nipping stations is adjustable in accordance with the thickness of the package to be nipped. The separation of the jaws at the nipping stations must be similarly adjustable. To this end, the toggle links 93 (Figs. 2 and 4) connecting the movable jaws to their connecting rods 94 are each made up of two parts 156, 157 which are screw-threaded by right and the other left-handed and are connected by a correspondingly screw-threaded union 158. Adjustment of the length of the links 93 makes no material difference to the length of the stroke imparted to the jaws connected to them but varies the initial and final separation of the jaws in each pair.

To prevent movement of the packages relatively to the conveyor, pushers 160 one of which is shown separately in Figs. 9 and 10 are carried by the brackets 22. These pushers are of automatically adjustable width in accordance with the separation of the guide walls and the nipping jaws.

Where very thin packages are being nipped, the brackets 22 can serve as pushers by themselves, their width and setting on the plates 10 of the conveyor being suited to the minimum separation of the guide walls of the jaws. For thicker packages, the pushers 160 are mounted on the brackets. Each pusher comprises a supporting plate 162 having a dovetailed slot 164 in which a dovetail 166 on the brackets 22 can be engaged. The plate 162 supports two pusher plates 168, 169 which are mounted on pivots 170. The pusher plates are urged outwards by springs 172.

The pusher plate 168 is on the front side of the machine, that is to say, on the side of the fixed guide plates and the fixed jaws. Its spring 172 keeps it pressed against a pin 174 on the supporting plate 162 so that it is just clear of the fixed guide plates and the fixed jaws. The pusher plate 169 is pressed by its spring 172a against the adjustable guide plates and the adjustable jaws, there being no stop corresponding to the pin 174. Two different settings of the pusher plate 169 are shown in full and chain lines in Fig. 9 corresponding to two different settings of the jaw 20.

With this arrangement, the pusher plates 168, 169 adjust themselves to the separation of the parts between which they lie and ensure that the package will be urged forward with the conveyor whatever the width of the package may be.

As shown in Fig. 11, the pusher assembly 160 is held positively in position on the bracket 22 by a headed pin 176. The shank of the pin fits in a hole 178 (Fig. 9) in the supporting plate 162 and its head fits in a recess 180 in the bracket 22. The pin is kept in position by a spring 182. To mount a pusher assembly 160 on the bracket, the spring 182 is pulled back as shown in chain lines in Fig. 11, the pin 176 is pushed back so that it does not project in front of the bracket and the assembly is engaged on the dovetail 164. When the assembly is in position on the bracket,

release of the spring 182 causes the pin 176 to be pressed forward and to engage in the hole 178. The conveyor is driven and the movable jaws are reciprocated by a motor 184 (Figs. 1 and 4) connected by a V-belt drive 186 to a shaft 188. The shaft 188 is connected by reduction gearing 190 to a shaft 192 which drives the eccentric 96 through which the jaws are reciprocated. The shaft 188 is also connected by bevel gearing 194 to the shaft 38 by which the cams 36 and 150 are driven.

The nipping pressure applied by the jaws is substantial. Yokes consisting of a pair of heavy plates 196 connected together by distance pieces 198 are provided at each nipping station and provide the necessary reaction abutment.

It will be seen that the machine is almost fully automatic. It needs only one attendant whose task is simply to load the packages on to the conveyor at the loading station. An output of 18-20 nipped packages per minute can easily be achieved.

We claim:

1. A book nipping machine comprising an intermittently driven conveyor means on which packages having a spine edge and a fore-edge are conveyed edgewise; a first and a second pair of nipping jaws, said means intermittently conveying the packages to and through said respective pairs of jaws, said first jaws having rigid spine-nipping portions and having relatively flat resiliently urged package gripping portions there-adjacent extending to the fore edge of the package, the latter portions applying light pressure to the package while the former portions apply heavy pressure thereto and said second jaws being formed similar to said first jaws but reversed with respect thereto so as to apply a lighter pressure near the spine edge and a heavier pressure near the fore-edge.

2. In a nipping machine according to claim 1, said resiliently urged gripping portions normally extending inwardly toward each other beyond said nipping portions so that the lighter pressure in each operation is applied to the package before the heavier pressure, and is maintained while the heavier pressure is applied.

3. In a nipping machine as set forth in claim 1, said jaws having horizontal recesses in their opposed faces; a gripping portion set into each recess; and spring means for yieldably urging the said portions inwardly toward each other, the spring-urged portions applying said lighter pressure against the package as the jaws close thereon.

4. In a nipping machine as set forth in claim 1, ejector means synchronized with the intermittent motion of the conveyor, said means being adapted to eject from the conveyor the nipped packages as they emerge from said second pair of jaws.

5. In a nipping machine as set forth in claim 1, guide walls along the conveyor, means for adjusting the spacing between the guide walls, and pushers attached at intervals to said conveyor for preventing movement of the packages relatively to the conveyor, said pushers each comprising a pair of plates yieldably urged outwardly toward the guide walls so as to adjust themselves to the spacing between the guide walls.
- 10 6. A machine of the character described comprising a conveyor for packages to be nipped; means for driving said conveyor intermittently; two pairs of spaced nipping jaws arranged so that packages on said conveyor are conveyed between and past them; means for operating said jaws to nip said packages, said pairs of jaws being timed for actuation so that the packages are nipped by the jaws during pauses in the movement of said conveyor; and pushers attached at intervals to said conveyor and comprising laterally adjustable members.
- 15 7. A machine of the character described comprising a conveyor for packages to be nipped; means for driving said conveyor intermittently; two spaced pairs of nipping jaws arranged so that packages on said conveyor are conveyed between and past them; means for operating said jaws to nip said packages, the jaws being timed for actuation so that the packages are nipped by the jaws during pauses in the movement of said conveyor; guide walls arranged laterally opposite each other on the feed side of said pairs of jaws; means for adjusting the separation between the guide walls; and pushers attached at intervals to said conveyor for preventing movement of the packages relatively to the conveyor, said pushers comprising a pair of plates yieldably urged outwardly toward the guide walls so as to adjust themselves to the separation of the guide walls.
